UNITED STATES PATENT OFFICE

WILLIAM C. WILSON, OF PORT WASHINGTON, NEW YORK

SCREEN

Application filed August 18, 1925. Serial No. 50,911.

This invention relates to improvements in screens.

One of the objects of this invention is to provide a screen which is capable of being readily and quickly repaired and from which defective or worn out wires may be removed and replaced with great dispatch and without dismounting the screen from its operative position.

10 Another object of the invention is the production of a flat screen having wires which will not have a tendency to sag and which may be drawn taut and held in this taut condition.

15 Another object of this invention is to enable any elongation of the wires due to stretching in use to be readily and easily taken up or compensated for.

Still another object of my invention is to enable the supporting of a series of longitudinal wires in a curvilinear path so that the strands of wire passing may be more equally and readily stretched and tightened.

20 Another object of the invention is to provide a screen of the type specified which will be composed of a series of separately adjustable sections whereby the wires of one section may be repaired or tightened without affecting the wires of any other section.

30 Another object of the invention is to produce a flat screen in which the usual sagging at the middle thereof will be avoided.

Another object of the invention is to provide wire-supporting means which will accurately space longitudinal-wires to produce an effective screening of the material operated upon.

35 Another object of my invention is so to mount wire-supporting bars having spacing grooves that, by a simple manipulation, a new groove portion may be made available to replace grooves in which the walls are worn out.

40 Another object of the invention is to provide a screen which will be extremely rigid, strong and durable and will be effective to screen sand or the like.

45 With these and other objects in view, the invention comprises the combination of members and arrangement of parts so combined

as to co-act and cooperate with each other in the performance of the functions and the accomplishment of the results herein contemplated, and comprises in one of its adaptations the species or preferred form illustrated in the accompanying drawings, in which:

Fig. 1 is a fragmentary view, in plan, of a screen embodying my invention;

Fig. 2 is a similar view in side elevation of the screen shown in Fig. 1;

Fig. 3 is a section on the line 3—3 of Fig. 1 looking in the direction of the arrow;

Fig. 4 is an enlarged fragmentary section of one end of a screen embodying my invention;

Fig. 5 is a fragmentary transverse section taken in part at one side of one of the wire-supporting cross-bars and in part through the outer sleeve of a portion of another bar;

Fig. 6 is an enlarged view, in plan, of one end of the bottom of said screen.

Referring now to these drawings, which illustrate a preferred embodiment of my invention, a suitable rigid frame may be formed in any conventional manner. As illustrated, 1, 1' indicate side-frame members comprising channel bars which are suitably spaced and held rigid by end frame members 2, 2' comprising, as shown, angle-bars. Said side and end frame members are connected at the front end by fastening members 3 comprising, as illustrated, relatively long angle-bars and at the rear end by fastening members 4 comprising relatively short fastening angle-bars. The end frame members preferably project outwardly beyond the side members and each of said fastening members has one of its flanges viz, its vertical flange connected to a side frame member by bolts 5 and its other flange, viz, its horizontal flange connected to an end frame member by bolts 6. In broad embodiments such as that shown, I preferably insert a longitudinal stiffening partition bar 11, which is suitably fastened to the end bars.

In accordance with the preferred form of my invention illustrated, the side channel-iron frame members are provided with a series of pairs of rod-mounting apertures 7

extending from a point near one end to a point near the opposite end in a curvilinear path, the members of each pair registering with each other and the pairs being suitably spaced. Mounted in the apertures 7 in spaced relationship are a series of wire-supporting cross-rods 8, one bar being mounted in a pair of these apertures 7. In the double screen shown, I have mounted on each rod, a pair of sleeves 9 each having a series of peripheral grooves 10 suitably spaced from each other, these grooves preferably extending completely around the circumference of the sleeve for a purpose which will be hereinafter explained.

In the preferred embodiment shown, one end of the screen is provided with a single stationary wire-fastening plate 12, secured to the end bar 21 by bolts 12^a and provided with a series of holes 13, through which are inserted the ends 14^a of a series of wires 14, said ends 14^a being bent into hook-shape substantially as shown in Figs. 3, 4 and 6. The hook-shaped ends are clamped in place on the end plate 12 by a clamping plate 15 which is fastened beneath the top plate 12 by a series of bolts 16. This end of the wire fastening or mounting elements is, therefore, preferably retained in fixed position. The holes in the said plate 12 are preferably arranged in rows inclining forwardly and rearwardly to form a zig-zag conformation and the hook-shaped ends of the wires at this end of the frame are securely locked to the fastening plate in stationary position. The wires 14 are individually strung over cross rods 8 and assume a curvilinear path, and each wire is seated in a longitudinal series of grooves 10 in the peripheries of the sleeves 9, the grooves on a sleeve being spaced from each other so as to space the wires and retain them securely in properly spaced relationship. The opposite end of the wires 14 are fastened in fastening apertures 17 in a series of sectional fastening plates 18 which preferably have the fastening apertures similarly arranged in zig-zag conformation. Each of these sectional fastening plates 18 are adjustably mounted in relation to the stationary end bar 2 of the frame. As illustrated, the wires are similarly passed through the holes 17 and turned into end hooks 14^b beneath the same and are then clamped in place on the plates 18 by clamping plates 19 fastened beneath the said clamping plates by bolts 20. The apertured fastening plates 18 are adjustably mounted in relation to the bar 2 by fastening to the bottom surface of each plate, an angle bar 21 spacing the same from the stationary frame bar 2 and adjustably connecting a vertical flange of said angle bar 21 with a vertical flange 2^a of the angle bar 2 by screw-threaded draw bolts 22 having nuts 23 which, upon tightening up, will obviously draw the fastening plate 18 to which the bolts

are connected toward the bar 2 and will thus apply tension on the wires 14.

It will be seen that these wires 14 may thus be readily and quickly tensioned and that a section of the same may be operated upon for repair purposes without disturbing the other sections. Also that by reason of the curvilinear support of such wires, the same may be tightened up and made as taut as required and, when so tightened up, may be maintained in taut condition indefinitely. Furthermore, that any elongation in the wires due to stretching while in use may be readily taken up by a tightening of the draw bolts 22 and that when the walls of that portion of the grooves 10 in which the wires are seated are worn down, new grooves may be provided by simply rotating a sleeve on a bar to bring to the top a new portion of the continuous peripheral groove 10.

It will thus be seen that I provide a screen which may be readily and quickly repaired; that defective wires may be removed and replaced without removing the screen from its mounted position; that I provide a flat screen in which the wires may be drawn taut and held in this condition; that any elongation of the wires due to stretching in use may be readily and easily taken up and compensated for; that I produce a screen of a flat type in which longitudinal wires may be retained in spaced relationship and will be supported on a series of cross-bars arranged in a curvilinear path so that the strands of wire passing over the same may be more readily tightened to form a drum like structure; that I provide a screen of the type specified which will be composed of a series of separately adjustable sections whereby the wires of one section may be repaired or tightened without affecting the wires of any other section; that I produce a flat screen which will avoid the usual sagging at the middle thereof; that I provide supporting and wire-spacing bars in which, by a simple manipulation, a new groove portion may be made available to replace grooves in which the walls are worn out; and that I provide a screen which will be extremely rigid, strong and durable.

Having described my invention, I claim:—

1. A screen embodying a suitable frame composed of side and end members, wire-fastening means at one end of said frame, a plurality of independently mounted and removable wire-fastening plates mounted at the opposite end of said frame, a series of wires connected by a non-adjustable connection with each of such wire-fastening plates and with the opposite end of said frame, means for moving said plates to apply tension to said wires, and means for supporting said wires between the ends of said frame.

2. A screen embodying a suitable frame composed of side and end members, wire-fastening means at one end of said frame, a plu-

rality of independently mounted and removable wire-fastening plates mounted at the opposite end of said frame, a series of wires strung between each of such wire-fastening plates and the opposite end of said frame, removable clamping means for connecting the wires to said series of plates, bolts for moving said plates relatively to said frame to tension the said wires, and means for supporting said wires between the ends of said frame.

10 In witness whereof, I have signed my name to the foregoing specification.

WILLIAM C. WILSON.
